UNITED STATES PATENT OFFICE

149,638

DESIGN FOR A SEWING KIT

Theodore Poole Heider, East Orange, N. J.

Application January 25, 1947, Serial No. 136,403

Term of patent 14 years

(Cl. D3—19)

To all whom it may concern:

Be it known that I, Theodore P. Heider, a citizen of the United States, residing in East Orange, in the county of Essex and State of New Jersey, have invented a certain new, original, and ornamental Design for a Sewing Kit, of which the following is a specification, reference being had to the accompanying drawings, forming a part thereof and in which:

Figure 1 is a top plan view of a sewing kit embodying my new design;

Fig. 2 is a side elevational view thereof;

Fig. 3 is a top plan view of the bottom part of the sewing kit, and

Fig. 4 is an elevational view of the side of the sewing kit opposite to that illustrated in Fig. 2, showing the hand grip therefor.

I claim:

The ornamental design for a sewing kit, substantially as shown and described.

THEODORE P. HEIDER.
